Attorney

UNITED STATES PATENT OFFICE

IRWIN J. SIEBERT, OF CLEVELAND, OHIO

AMUSEMENT DEVICE

Application filed June 17, 1931. Serial No. 545,116.

My invention relates to amusement devices, more particularly to amusement devices of the type known as roundabouts, and it consists in the combinations, constructions, and arrangements herein shown and described.

Many devices of the type known as roundabouts have heretofore been provided which impart to the passengers or users thereof a series of unusual motions, affording recreation and pleasure to said occupants.

It is an object of my invention to provide a device that will impart a new series of unusual motions to the passengers for the delight and amusement of the same.

15 A further object of the invention is to provide a device of the type described which has few parts, does not get out of order easily, and is simple to manufacture.

Other objects and advantages will appear 20 as the specification proceeds and the invention will be more particularly defined in the appended claims.

My device is illustrated in the accompanying drawing forming a part of this application, in which

Figure 1 is a top plan view of my invention, with parts thereof shown in phantom for clearness in illustrating the operation, and

Figure 2 is a side elevational view with 30 parts thereof shown in section for clearness of illustration.

In carrying out my invention I make use of a platform 1 tilted at any suitable angle to the horizontal, as shown in Figure 2, and 35 rigidly set up in this position by means of framework. On top of this framework I place a circular track, 3, shown in section in Figure 2 and in phantom in Figure 1.

This track, 3, supports for rotation thereon a circular platform, 4, having rollers or casters, 5, positioned therebeneath at various points thereabout. A roller, 6, takes up any thrust occasioned by this rotation, due to the exercise of the force of gravity thereon. This 45 platform is mounted for rotation with a shaft, 7, positioned for rotation in framework 8, normal to the plane of the platform.

Positioned above the platform 4 and fixedly 50 mounted on the shaft 7 is a hub member, 9. The platform 4 is provided with a plurality of

laterally extending sweeps, 10, therebeneath, radiating from the center. Any number of these sweeps, 10, may be provided. In this embodiment, however, I have shown only six. The casters, 5, may be secured to these if desired. 55

Rotatably attached to pivots, 11, extending through each of these sweeps and the platform 4, are cars, 12, which may be of any suitable shape and for the reception of any 60 number of passengers, but which in this form are shown as being adapted to receive a single passenger. Each of the sweeps is further provided with an upstanding stud, 13, placed in spaced relation to the point 11, and extending above platform 4 to engage the sides of the cars 12 for operations that will be made clear. 65

For rotating the platform, the shaft 7 is provided with a large gear, 14, mounted for 70 rotation with the shaft 7, and secured to the lower part of platform 4. This gear is driven by a pinion, 15, mounted on a drive shaft, 16, secured in framework 17 and driven by a motor 18 through bevel gears 19 and 20. A gear box, 21, having a gear shift lever, 22, controlled by operating link, 23, acts to regulate the speed of the motor. A rheostat, 24, controls the amount of electricity flowing through the motor conduit, 25, which may 75 be connected to any suitable source of electrical energy, by means of switch 26.

At 27 I show a loading platform for allowing ingress and egress of the passengers to and from the cars. 80

From the foregoing description the use and operation of my device is easily understood. When the operator desires to start the rotating platform, he simply closes switch 26 to operate the motor. Then, by use of 85 the gear shifting mechanism, he accelerates or decelerates the speed of rotation of the platform as desired.

During this operation the cars will be carried from the lowermost position, shown at 90 the right of Figure 2, to the uppermost position, shown at the left of said figure. The stops or lugs, 13, during this motion will engage the cars and hold them stationary relative to the platform until the same reach the 95 100

upper positions, whereupon they will be thrown forwardly relative to the motion of the platform under the action of the force of gravity with a violent "whipping" action which will greatly add to the enjoyment and amusement of the passengers. The car will then oscillate about its pivot, 11, as shown by the dotted line views in Figure 1, and then assume the positions shown until it again engages the stop, 13, for repetition of the operation.

These variable motions of the cars are well accommodated by the use of a pair of casters, 28, positioned thereon and capable of turning in all directions.

It is thus seen that I have provided a round-about which produces a number of novel motions to the enjoyment and merriment of the passengers.

What I desire to claim and secure by Letters Patent is:

1. In an amusement device, a rotatable platform positioned at an angle to the horizontal, cars movable upon and pivotally mounted relative to said movable platform, stops for limiting motion of said cars about their pivots, and means for rotating said platform to impart variable motions to said cars.

2. In an amusement device, a platform positioned at an angle to the horizontal, cars movable upon said platform and pivotally secured thereto, stops on said platform in spaced relation to said pivotal connections for engagement with said cars, and means for rotating said platform for imparting variable motions to said cars.

3. In an amusement device, cars, means for pivotally mounting said cars, stop means positioned in the path of movement of each of said cars, and means for rotating said cars at an angle to the horizontal for imparting variable motions thereto.

4. In an amusement device, pivot means, cars mounted on said pivot means, stop means positioned in the path of movement of each of said cars, and means for moving said pivot means in a plane at an angle to the horizontal for imparting variable motions to said cars.

5. In an amusement device, pivot means, cars mounted on said pivot means, stop means positioned in the path of movement of each of said cars, and means for rotating said pivot means in a plane at an angle to the horizontal, whereby a whipping action is imparted to said cars.

IRWIN J. SIEBERT.
